UNITED STATES PATENT OFFICE.

JEREMIAH H. WHITEHOUSE, OF SPRINGFIELD, MASSACHUSETTS.

CALENDERING-MACHINE.

1,123,968.

Specification of Letters Patent.

Patented Jan. 5, 1915.

Application filed January 13, 1912. Serial No. 670,975.

To all whom it may concern:

Be it known that I, JEREMIAH H. WHITEHOUSE, a citizen of the United States of America, residing at Springfield, in the 5 county of Hampden and State of Massachusetts, have invented new and useful Improvements in Calendering-Machines, of which the following is a specification.

This invention relates to calendering machines especially for calendering paper in the manufacture of glazed paper. In these machines, it is customary to run the paper between two rolls,—one running faster than the other,—having a greater peripheral 10 speed than the surface of the paper, whereby the friction of the fast running roll on the paper gives the desired glazed surface. It has been of the utmost importance in designing these machines to provide some satisfactory means for driving the slow roll relative to the fast one. The speed ratio between these two rolls must be as nearly constant as is possible. If in the operation 15 of the machine, the speed of one roll changes relatively to the other, no matter how little, in any intermittent manner the paper is injured.

It is the object of this invention to provide means for keeping the speed ratio of 20 the two rolls absolutely constant with a minimum expense in the manufacture of the machine.

In the drawings forming part of this application, Figure 1 is a side view of the 25 assembled machine. Fig. 2 is a front view of the same.

Both views of the drawing show the paper as it passes through the machine.

On the frame *l* three shafts *b*, *e*, and *d* 30 are mounted. The belt *a* drives the pulley *t* fast to one end of the shaft *b* on the latter of which the fast roll *o* is fixed. A sprocket wheel and pulley are mounted on the other end of the shaft *b*. Rolls *p* and *q* are 35 mounted on the shafts *e* and *d* respectively. A roll *j* of paper to be glazed is rotatably mounted on the standards *n*. This roll of paper passes under the weight tension device *k* up against the roll *p* and partly 40 around this roll and between this roll and the top roll *o*; then the paper is wound up on a roll rotatably mounted on standards *m*. This latter roll is driven by a belt *g* from 45 the pulley on one end of the shaft *b*.

It has been customary in known machines 50 to operate the shaft *b* by a pulley driven

from the main shaft. As the paper passes between the rolls *p* and *o*, the latter bears on the paper with a pressure regulated by the device *r*. As the roll *o* rotates, it continually tends to drive the paper, the roll *p*, and through it, the roll *q* which is in direct contact with said roll *p*.

As it is necessary to prevent the surface of the paper and roll *p* from having as great 55 a speed as the roll *o*, designers have, in the past, connected the shafts *b* and *d* by an intermeshing spur gear train which positively prevented the roll *p* from traveling beyond a certain speed. This method proved 60 65 unsatisfactory because the intermeshing gears had a certain amount of back lash and this back lash allowed the gears to "chatter" intermittently, which changed the speed ratio of rolls *o* and *p* and caused the 70 75 "gear marks" on the paper. These marks are roughened or crimped portions on the surface of the paper due to the change in the speed ratio of the two rolls. Such marks are, of course, highly objectionable 80 in the finished product. The use of herring-bone gears has proved highly satisfactory in the results obtained, but the initial expense of these gears is prohibitive.

The objections to belt connections between 85 the shafts *b* and *d* are that in order to keep the speed ratio constant, countershafts and large pulleys and belts must be used, for if a belt passed directly over the pulleys on the shafts *b* and *d* the slip would prevent the 90 constant speed ratio. The use of these large pulleys, belts, and countershafts takes up a great deal of room, shuts out the light, and creates dust.

With belts or gears, the horse power 95 necessary to drive the machine is considerable. By the invention herein described a considerable saving in power is obtained in addition to obtaining the desired improvements in the operation of the machine.

Applicant has found, after experimenting with all the methods mentioned, that a special form of link chain may be used for the purpose desired with a minimum amount of expense, space, and trouble. The use of 100 this special form of chain is specifically illustrated in Figs. 1 and 2. It is known as the silent type chain and differs in many essential respects from block or roller chains. The chief difference is that the chain automatically compensates for wear both of its 105 own parts and the teeth of the sprocket 110

wheels, and thereby keeps the pitch line constant and never slips, as do other chains, so that the speed ratio of the two shafts driven by the chain is kept absolutely constant. This type of chain is well known in the chain art and is diagrammatically illustrated in Fig. 1 wherein the peculiar form of links used are shown. The patent to Warren J. Belcher, No. 959,046, dated May 10 24, 1910, shows the silent type chain more in detail.

In Fig. 1, as shaft *b* rotates very rapidly, it tends to drive the paper and roll *p* just as fast. The roll *p*, however, bears directly on the roll *q* and before the roll *p* can rotate it must rotate the roll *q*. The roll *q*, however, is held from rotating beyond a certain speed by the sprocket *f*, chain *e*, and the sprocket on the shaft *b*. This chain gear train determines absolutely the speed ratio of the rolls *o* and *p*. It can be also seen from Fig. 1 that the chain is acting as a hold back for the shaft *d*, for if it were driving, the slack and tight sides of the chain would be reversed. The use of any other chain than the special one mentioned would not give the results mentioned. By the arrangement described, applicant gets a constant speed ratio between the operating rolls of a calendering machine in a novel, efficient, and economical manner.

What I claim, is:—

1. A calendering machine having, in combination, a roll with means for driving it at high speed, a second roll between which and the first roll paper can be calendered, a third roll in contact with the second roll, and means to insure a constant speed ratio between the first roll and each of the other two comprising a sprocket-wheel on the shaft of the first roll, a second sprocket-wheel on the shaft of the third roll, and a chain of the silent type passing over said sprocket wheels whereby the first roll will be prevented from changing the desired speed ratio, all for the purpose described.

2. A calendering machine having in combination, a roll with means for driving it at high speed, a second roll between which and the first roll paper can be calendered, and means to insure a constant speed ratio between the first roll and the second roll, wherein the speed of the latter is less than the former roll, said means comprising a braking device for said second roll, and a chain of the silent type connecting the shaft of the first roll with said braking device, all for the purpose described.

JEREMIAH H. WHITEHOUSE.
